UNITED STATES PATENT OFFICE.

EDWARD S. MARSH, OF ROCHESTER, NEW YORK, ASSIGNOR TO TAYLOR INSTRUMENT COMPANIES, OF ROCHESTER, NEW YORK, A CORPORATION OF NEW YORK.

TIME-CONTROLLED VALVE-OPERATING MEANS.

Application filed July 12, 1920. Serial No. 395,619.

To all whom it may concern:

Be it known that I, EDWARD S. MARSH, a citizen of the United States, residing at Rochester, in the county of Monroe and State of New York, have invented certain new and useful Improvements in Time-Controlled Valve-Operating Means; and I do hereby declare the following to be a full, clear, and exact description of the same, reference being had to the accompanying drawings, forming a part of the specification, and to the reference numerals marked thereon.

This invention relates to time controlled valve operating means, such as are commonly employed for vulcanizers and other processing containers and, more particularly, to means of this character employing fluid pressure as a motive force for opening or closing main operating valves at the end of a predetermined period of time. The chief object of the invention is to provide an improved device of this kind which is convenient, reliable and accurate in operation, simple and compact in construction and economical to manufacture. To these and other ends the invention resides in certain improvements and combinations of parts, all as will be hereinafter more fully described, the novel features being pointed out in the claims at the end of the specification.

In the drawings:

Figure 1 is an elevation of the main parts of a valve operating means embodying the present invention, enclosed in a casing;

Figures 2 and 3 are enlarged elevations showing the secondary or fluid pressure valve in different positions;

Figure 4 is a section on the line 4^a—4^a of Figure 2.

Figure 5 is a section on line 5^a—5^a of Figure 4.

Figure 6 is a section on the line 6^a—6^a of Figure 4.

Figure 7 is a detail view of the time cam, and

Figure 8 is a diagrammatic view of the apparatus as a whole.

Similar reference characters throughout the several views indicate the same parts.

The embodiment of the invention herein shown and described is selected merely by way of illustration of the principle and application thereof and is capable of various

modifications and other uses. The present embodiment is disclosed as applied to the purpose of controlling a fluid container 10, Figure 8, such as is commonly employed in various processes for subjecting material to be treated to the action, for example, of a heating medium such as steam which is supplied to the container through a pipe line 11 controlled by a valve 12 of the well known diaphragm type operated by the fluid pressure actuating means 13 and the spring shown. In the present case, for a purpose which will presently appear, the actuating means 13 is preferably of the double diaphragm variety known in the art and capable of operation by fluid pressure regulating means with which pipe 14 is connected for regulating the temperature or pressure within the container, and also by the mechanism embodying the present invention which is connected with the valve by the pipe line 15. Container 10 has connected therewith also a discharge or blow-off line 16 for emptying the same of the heating medium, water of condensation and the like, controlled by a valve 17 having the usual fluid pressure actuating means 18 and the spring shown in the drawings. Actuating means 18 is supplied with fluid under pressure through a pipe line 19 with which the line 15 is connected and it will be understood that valve 12 is of the so-called direct acting type which is closed by the application of fluid pressure, while valve 17 is of the reverse acting type which is opened by the application of fluid pressure, so that when pressure is admitted to the line 19 it closes valve 12 to cut off the supply of steam or other heating medium, and opens valve 17 to exhaust the same from the container thereby quickly terminating the process at the time desired.

The time controlled operating means for the main valves 12 and 17 is enclosed within the casing 20 with which the fluid pressure line 19 connects and also the line 21 from a suitable source of pressure. A moisture trap 22 and also a pressure gauge 23 may be inserted in the latter line if desired.

The secondary or fluid pressure valve governing the supply of pressure from line 21 to line 19 comprises preferably a housing 24 secured as by means of screws 25, Figure 1, to the back of casing 20. The housing has formed therein, Figure 4, a substantially

cylindrical valve chamber 26, opening into the housing from the back of the latter and there closed by a plug 27 threadedly engaging the end of the chamber. Closely and rotatably fitted within the latter is the valve body 28 in the shape of a disk having a stem 29 guiding the valve and rotatably carried in a bore opening through the front of the housing 24. The stem projects 10 through the front of the latter and has a reduced angular portion 30 to which the valve actuating means is secured. The valve disk has an opening or port 31 from front to back therethrough and also an elongated 15 port or depression 32 in its forward surface. Communicating with the valve chamber back of the disk is an opening 33 with which is connected a pipe 34 carried around the side of the casing 20, Figure 1, and 20 connected with a union 35 supported in a bracket 36 on the casing and to this union is connected the pressure supply line 21. The valve chamber and the port 31 of the valve disk are thus subjected at all times 25 to the fluid pressure.

The forward part of the housing 24, opposite the valve stem 29, preferably has formed therein an angular opening or passageway 37 which turns rearwardly and 30 opens through the forward wall of the valve chamber in position to register with the slot or port 32 in the forward side of the valve disk in certain positions of the latter. Connected with the opening 37 is a pipe 38 carried around the side of the casing and 35 connected with a union 39 supported in a bracket 40 thereon, the union 39 having connected therewith the line 19 leading to the main valve. Spaced from the opening or 40 passageway 37 is a similar passageway 41 opening into the valve chamber on the forward side of the valve disk in position also to register with the slot or port 32, and connected with this passageway is a pipe 45 42 which opens to the atmosphere. At 43 is a spring plate bearing against the valve housing and a part on the valve stem to hold the valve disk tightly against the forward wall of its chamber. Referring to Figures 50 2 and 3 where these various ports and openings are shown in dotted lines, it is seen that, in the rotary position of the valve disk shown in Figure 2, opening 37, and therefore the main valve supply line 19, is connected 55 by means of the slot or port 32 with the vent passageway 41, so that in this position the pressure is removed from the main valve 12 and the latter is open to supply steam to the container while discharge valve 17 is 60 closed. In the position of the valve disk shown in Figure 3, however, slot or port 32 is out of register with opening 37, and port 31 registers with the latter so that pressure is thus transmitted to the latter and 65 to line 19, closing supply valve 12 and open-

ing discharge valve 17 for terminating the process.

The means for operating the secondary or fluid pressure valve comprises, preferably, a frame 44 having an angular opening embracing the angular portion 30 of the valve stem and fixed to the latter by means of a set screw 45. Frame 44 has a forked or yoke portion 46 between the arms of which is pivotally secured, as by means of a pin 47, a radially extending arm 48, which is normally yieldably maintained in such radial relation, as shown by full lines in Figure 4, by means of a coil spring 49 secured by a screw 50 on the frame 44 and having an angular end cooperating with a pin 51 on the arm. It is apparent however that the end of the spring is so shaped as to permit the arm to be moved to the inclined position shown in dotted lines, for a purpose presently to be described, and the arm is yieldably held in such inclined position by the spring until it is returned to the position shown in the full lines. The outer end of the arm is provided with a thin knife like edge 52 for close cooperation with a time driven cam which will now be described, the end 52 being urged into engagement with the cam by a coil spring 52^a fixed at one end to the back of the casing and at its other 90 end to a short arm on the frame 44.

A means is provided for maintaining arm 48 and the valve in the operating position shown in Figure 2, with the steam supply valve 12 open and the discharge valve 17 closed, until the predetermined time arrives for releasing the arm and valve to permit movement of the latter by its spring 52^a to the position shown in Figure 3, thus terminating the process. This means comprises, preferably, a substantially circular cam 53, Figures 1 and 7, adjustably and removably fixed on a spindle 54 by means of a thumb nut 55. As shown in the drawing, spindle 54 carries also a rotatably adjustable 105 and removable cam 56 with which cooperates an arm 56^a of a mechanism for regulating the temperature in container 10 during the process, as disclosed in my copending application for patent for time-controlled regulating devices, such mechanism being adapted for connection with valve 12 by the fluid pressure line 14. Spindle 54 has fixed thereon also a gear 57 meshing with a gear 58 of any suitable time mechanism or clock shown as enclosed within an inner casing 59 secured as by means of screws 59^a on the back of casing 20 and having a suitable winding stem 60. Nut 55, of course, serves to clamp the cams 53 and 56 against gear 57 in fixed relation to the spindle after the cams have been rotarily adjusted to desired position thereon. Cam 53 has in the main a circular profile against which arm 48 bears so that movement of the 110

latter is restrained until the rotation of the cam brings under the point of the arm the abrupt wall 61 of a depression in the cam which allows the arm to drop into contact with an opposing inclined wall 62 of the depression, the function of which is to move the arm about its pivot transversely of its direction of rotation or substantially in the plane of the valve stem, so that the arm is quickly thrown out of engagement with the cam and is swung toward the left by its spring 52 to the position of Figure 3, for operating the valves in the manner described to terminate the process. By this means the arm is instantly released from the cam and permitted to swing through a substantial angle for operating its valve. In order to reset the arm on the cam, however, to repeat the operation, the arm may be conveniently turned about its pivot far enough to clear the cam and swung toward the right and reengaged with the circular profile of the cam. Extreme movement of the arm is limited by the stop pins 63 shown in Figure 1. When it is desired to remove cams 53 and 56 from spindle 54 for the purpose of substituting a different regulating cam 56, arm 48 may be swung to the position shown in dotted lines in Figure 4 in which position it is out of the way of the cams while the latter are being removed and replaced.

Cam 53 is conveniently provided with a zero mark, as shown, which is adjacent a time scale on the regulating cam 56 and is properly located with reference to its operating shoulder 61 so that, with cam 56 in zero position as at the start of the process, the zero of cam 53 may be rotated through a number of hours or fractions thereof as indicated by the scale on cam 56, corresponding to the desired time period of the process, and the location of the zero point of cam 53 in this manner opposite the time on the scale at which it is desired to terminate the operation automatically rotates the operating portion 61 of the cam to a position such that at the termination of the desired period the arm 48 will be released to terminate the process.

As apparent from the disclosure, the device is simple and compact in construction, requiring comparatively few parts of practical design and low cost of manufacture, and the various parts are so constructed and arranged as to afford a mechanism which is convenient, reliable and accurate in operation.

I claim as my invention:

1. In a regulating apparatus, the combination of a regulating element, a part connected with the element and movable to move the same, said part having also a second movement independent of movement of the element, means for effecting said first movement of said part, a cam for engage-

ment with said part to normally restrain said first movement having a portion formed to release said part for movement of the element and also a portion inclined to the direction of movement of the cam to effect said second movement of said part to release said part from the cam, and a time mechanism for driving the cam.

2. In a regulating apparatus, the combination of a regulating element, an arm on the element to control movement thereof, said arm being movable with the element and having also a second movement independent of the element, means for effecting said first movement of the arm, a spindle, a cam adjustably carried by the spindle for normally restraining said first movement of the arm having an abrupt depression for releasing said arm and adjacent thereto a portion inclined to the path of the cam to effect said second movement of the arm to release the latter from the cam, and time mechanism for driving said cam.

3. In a regulating apparatus, the combination of a rotary regulating valve, an arm connected for rotation with the valve and having also an idle pivotal movement transversely of said rotary movement, a spring for rotating said arm, an adjustable rotary cam having a peripheral surface normally restraining rotation of the arm with a radial depression therein for abruptly releasing said arm and also a surface extending transversely of said peripheral surface for effecting said idle movement of the arm to release the latter from the cam, and a time train for driving the cam.

4. In a regulating apparatus, the combination of a rotary regulating valve, an arm connected for rotation with the valve and having also an idle pivotal movement transversely of said rotary movement, a spring for rotating said arm, a rotary spindle, a cam adjustably carried by the spindle having a generally circular peripheral surface for engagement with said arm with a substantially radial depression therein for releasing said arm to normally restrain rotation of the arm and having also a surface inclined to the plane of rotation of the cam for effecting said transverse movement of the arm to release the latter from the cam, and a time train for rotating said spindle.

5. In a regulating apparatus, the combination of a regulating valve, a part connected with the valve and movable to move the same, said part having also a second movement independent of movement of the valve, means for effecting said first movement of said part, a rotary spindle provided with a dial, a cam rotatably adjustable on the spindle and having an index cooperating with said dial, said cam being formed with a peripheral surface engaging said part to normally restrain movement thereof and also

with an integral surface inclined to said peripheral surface for effecting said second movement of said part and releasing the latter from the cam, and a time train for 5 rotating said spindle.

6. In a regulating apparatus, the combination of a rotary regulating valve, an arm connected for rotation with the valve and having also an idle pivotal movement transversely of said rotary movement, a spring 10 for rotating said arm, a rotary spindle, provided with a time dial, a cam adjustably carried by the spindle having an index co-operating with said dial for indicating the 15 adjustment of the cam, said cam being formed with a peripheral surface engageable with said arm to normally restrain rotation of the latter and also with a surface transverse to said peripheral surface to effect 20 said idle movement of the arm to release the latter from the cam, and a time train for rotating said spindle.

7. In a regulating apparatus, the combination of a rotary regulating stem, a radially extending arm on said stem rotatable therewith and having also a transverse piv- 25

otal movement, spring means for rotating said arm and stem, spring means for retaining said arm in extreme positions of transverse movement, a rotary cam in the path of 30 rotary movement of the arm to normally restrain movement thereof having an abrupt depression therein for releasing said arm at a predetermined time and having also a portion adapted to effect said transverse 35 movement thereof, and time mechanism for rotating said cam.

8. In a regulating apparatus, the combination with a rotary valve provided with a stem, a frame on said stem, a radially extending arm pivotally mounted in said frame for movement substantially transverse to its rotation, spring means for rotating the arm and valve, and an adjustable rotary cam in the path of rotation of the arm provided 40 with a depression having an abrupt leading wall and an angularly turned rear wall 45 adapted to move the arm transversely clear of the cam, a spring for urging the arm to cam engaging position, and time mechanism 50 for rotating said cam.

EDWARD S. MARSH,
